UNITED STATES PATENT OFFICE.

EDMUND C. MORGAN, OF NEW YORK, N. Y.

APPARATUS FOR MINING PURPOSES.

1,333,627.

Specification of Letters Patent. Patented Mar. 16, 1920.

Application filed April 28, 1913, Serial No. 763,962. Renewed November 7, 1919. Serial No. 336,470.

To all whom it may concern:

Be it known that I, EDMUND C. MORGAN, a citizen of the United States, residing in New York, county of New York, and State 5 of New York, have invented certain new and useful Improvements in Apparatus for Mining Purposes, of which the following is a specification.

My invention relates to mining apparatus, 10 and one of its objects is the provision of means for cutting the material to be mined into large blocks and moving such blocks directly upon mine cars.

A further object of the invention is the 15 provision of means for cutting kerfs into the material to be mined and moving the dislodged material directly upon transporting means after being mined.

Another object of the invention is the 20 provision of a plurality of machines for dislodging the material to be mined in large blocks, and providing means co-acting with one of said machines for moving the dislodged material directly upon mine cars.

A further object of the invention is the 25 provision of a mining machine for producing a cut in the material to be mined so as to dislodge such material and provide means co-acting with the said mining machine to move the dislodged material directly after being mined to a mine car.

Other objects of the invention will appear hereinafter, the novel combinations and features of the invention being set forth 30 in the appended claims.

Referring to the accompanying drawings,—

Figure 1 is a plan view illustrating more or less diagrammatically the apparatus embodying my invention; 40

Fig. 1^a represents a detail view taken on the line *a*—*a* of Fig. 1.

Fig. 2 is an elevational view of a mining machine for producing vertical kerfs in the 45 mine walls;

Fig. 3 is a rear view of Fig. 2, with a portion of the truck broken away;

Fig. 4 is a view of a modified means of reversing the rotation or oscillation of the 50 means for moving the mining machine cutter to various arcs;

Fig. 5 is a plan view of the vertical kerf cutting machine shown in Fig. 2;

Fig. 6 is a sectional view taken on the 55 line 6—6 of Fig. 5, looking in the direction of the arrow;

Fig. 6^a is a vertical sectional view of Fig. 6 taken through the center of the bearing of the shafts 54 and 61.

Fig. 7 is an elevational view of a long 60 wall mining machine, which produces the vertical longitudinal kerfs, that separates the blocks of coal from the mine wall after the vertical and horizontal kerfs have been cut perpendicularly to the wall; 65

Fig. 8 is a plan view of the long wall mining machine shown in Fig. 7, certain portions being broken away;

Fig. 9 is an enlarged plan view of a portion of Fig. 1, to show certain rope connections; and 70

Fig. 10 is a rear elevation of the long wall mining machine shown in Figs. 1, 7 and 8, and shows particularly the rope connections and the pivotal connection of the 75 long wall mining machine track, by means of which the machine can readily be placed upon the truck or moved to mining position.

Referring to Fig. 1, it will be seen that a track 11 is provided for the mining machines substantially parallel to the face of the mine wall 12, into which the kerfs are to be cut. 13 designates a mining machine provided with feeding mechanism 14, the rope 15 of which is anchored at 16. When 85 the mining machine 13 is fed along the track 11 in the direction of the arrow 17, and the rotary cutter 18 is operated in the direction of the arrow 19, a horizontal kerf will be cut into the mine wall. I prefer to provide 90 a mining machine 13 which will comprise two horizontal rotary cutters 18 arranged one above the other a distance equal to the vertical dimensions of the block to be mined. 95

Following the mining machine 13 on the track 11 is another mining machine 20, which I have illustrated in detail in Figs. 2 to 6, inclusive. This machine is for the purpose of producing the vertical kerf 21 in the mine wall by means of the cutter 22, as 100 shown in Fig. 1. The machine 20 is so constructed that the cutter 22 may be fed forward in the direction of the arrow 23, or withdrawn in the direction of the arrow 24, without moving the truck on which the mining machine 20 is mounted. When the mining machine 25 produces the vertical cut along the wall at 26, by means of the cutter 27, and severs the block 28, the mining machine 20 may be shifted on its pivot 29 110 through an arc, as indicated at 30, so as to cause the cutter 22 to move the block 28

over onto the platform 31. The rope gear 55 associated with the long wall mining machine 25 may then be operated to cause the cutter 27 to move the block of material 28 along the platform 31 and upwardly to the platform 32 of the mine car, as indicated by the dotted lines shown in Fig. 1. The mine car 32 travels on the track 33, which is laid parallel to the mining machine track 11.

I will now describe the mining machine for producing the vertical kerfs 21 and for shifting such mining machine so as to move the severed block of coal rearwardly onto the platform 31. As shown in Figs. 2, 3 and 5, this machine is mounted on a truck comprising the wheels 34 and the platform 35. At the central portion of the platform, there is a turntable comprising a circular plate 36, having a depending cylinder or pivot 37, which is connected to a ring 38 by means of the retaining bar 39. It will therefore be seen that the pivot 37 fits into a circular opening in the platform 35, and that the ring 38 encircles the lower portion of the cylinder 37. The ring is, therefore, below the platform 35, being held in such position by the bar 39, and the circular plate 36 is above the platform. The mining machine is therefore securely connected to the platform 35 of the truck, but may be moved through an arc of circle by the rope gearing shown.

The main frame 40 of the mining machine is trunnioned on the circular plate 36 by being secured to the rock shaft 41, which is journaled in the bearings 42, 42, the latter being fixed to the peripheral portions of the disks 36 at diametrically opposite sides, as shown in Figs. 3 and 5.

Keyed to one end of the rock shaft 41 is a segmental worm gear 43, which meshes with the vertical worm 44 journaled in the bearings fixed to the turntable 36. At the upper end of the shaft of the worm 45 is a wheel 46 for manually turning the worm 45. When the worm 45 is thus actuated, motion is transmitted by means of the worm gear segment 43 to the shaft 41, and thence to the main frame 40 of the mining machine. The machine may therefore be moved to various positions vertically to effect vertical cuts into the mine wall at the desired elevation.

An electric motor 47 is mounted on the main frame 40 so as to slide longitudinally on the bottom of the main frame, between the guideways 48, 48', as shown in Fig. 6. The electric motor may be provided with a reversing switch 49 and a rheostat controller 50. To the motor shaft 51 is connected a pinion 52, which meshes with the large gear wheel 53. On the outer portion of the shaft 54 of the gear wheel 53 is keyed the sprocket 55, as shown in Figs. 5 and 6.

The shaft 54 extends through a bearing 56,

supported by the bracket extending rearwardly from the frame of the electric motor 47, and also to the bearing 57, which is also connected rigidly to the rear portion of the frame of the motor 47. At the inner end of the bearing 56 is keyed the gear wheel 58, which meshes with the gear 59, the latter being connected to the sleeve 60, which is loose on the shaft 61 (see Fig. 6). At the outer side of the bearing 57 is a gear 62, which is keyed to the shaft 54 and meshes with the idler gear 63. The gear 63 meshes with the gear 64, which is provided with a sleeve 65 mounted in the bearing 66 secured to the frame of the motor 47. The sleeve 65 is mounted loosely on the shaft 61 and is provided with clutch teeth 67 at its inner end. The sleeve 60 is also provided with clutch teeth 68 at its inner end. Between the clutch teeth 67 and 68 is located a clutch member 69, which is splined to the shaft 61, so as to permit longitudinal movement thereon, but compelling the said clutch member to rotate with the shaft 61. The clutch member 69 is provided with a circumferential groove engaged by a pin at the end of the lever 70, which is pivoted at 71 to the frame of the motor 47. A bearing 72 extending rearwardly from the frame of the motor 47 is provided for the shaft 61, as shown in Fig. 6, and outside of said bearing is a pinion 73 which is keyed to the shaft 61 and meshes with the rack bar 74, which is connected at its ends to the heads 75 and 76 of the main frame 40, as shown in Fig. 2.

When the motor is operated in one direction or the other, motion will be transmitted to the gears 52, 53, 58, 59, 62, 63 and 64, but they will rotate freely and no further operation will take place. When, however, the clutch 69 is thrown in, the feeding mechanism will be operated to move the cutter head forwardly or rearwardly. If the clutch 69 is thrown into engagement with the clutch teeth 68, the pinion 73 will be rotated in one direction, and if the clutch 69 is thrown in the opposite direction the rotation of the pinion 73 will be reversed. It will also be noted that the gearing is such that the forward feeding motion of the cutting mechanism may be carried on at a slow speed, because of the small gear 58 meshing with the larger gear 59, shown in Figs. 2 and 6. The return motion of the cutting mechanism may be accomplished much more quickly because of the large gear 62 being connected to a smaller gear 64.

At the central portion of the shaft 54 is loosely mounted a worm 77, which meshes with a worm wheel 78. The worm wheel 78 is mounted between the bearings 79 and 80, which are connected by the cross-piece 81. The bearing 80 is supported at the upper end of the bracket 82, which is secured to the

rear upper central portion of the frame of the motor 47. This construction is represented in plan in Fig. 5, and in dotted line elevation in Fig. 2.

- 5 The worm gear 78 is provided with a spline or feather that fits into the slot 83 which extends longitudinally of the shaft 84. The latter is journaled at its ends in the bearings 85 and 86, which are secured to the heads 75 and 76 of the main frame. At the rear end of the shaft 84 is keyed a bevel gear 87, which meshes with the bevel gear 88 keyed to the upper end of the shaft 89. The shaft 89 is journaled in the vertical bearing 90, secured to the head 76 of the main frame. The lower portion of the shaft 89 is journaled in the bearing 91, which is fixed to the rear end of the main frame 40. To the lower end of the vertical shaft 89 is keyed the rope drum 92, to which two ropes are secured at 93 and 94. The rope 95, which is secured at 93 to the drum 92, is wound in one direction, and the rope 96 that is secured at 94 to the rope drum 92 is wound in the opposite direction. The rope 96 is anchored at 97 to one end of the platform 35 of the truck that carries the mining machine, and the rope 95 is anchored at 98 to the opposite end of the platform 35.
- 20 When the lever 99, shown in Fig. 6 pivoted at 100 to the rear of the motor frame 47, is moved so as to throw in the clutch 101, the shaft 54 will be rotatively connected to the worm 77. When the electric motor 35 is operated, motion will be transmitted through the worm 77 and worm gearing 78 to the shaft 84. The rotation of this shaft will operate the bevel gears 87 and 88 and transmit rotary motion to the vertical shaft 89, and thence to the rope drum 92. As one of the ropes is wound up on the drum 92 and the other paid out, the entire mining machine will be shifted through an arc on the truck by the turntable connection. This 45 operation is particularly desirable to shift a block of coal after being entirely severed from the mine wall, over onto the platform to a position indicated by the block 28 in Fig. 1, after which the rope gearing associated with the mining machine 25 may be relied upon to slide the block of coal over the platform 31 onto the mine car 32.
- If it is not desired to reverse the motor by means of the reversing switch 49 when 55 the mining machine is to be returned to a position perpendicular to the mine wall, the modification shown in Fig. 4 will be used, by substituting for the bevel gears 87 and 88 and their supports a double bracket arm 102, with bevel gears 103, 104 and 105, with the clutch between the two latter. The double bracket arm 102 is secured to the rear end of the main frame 40 and comprises bearings 106 and 107 for an extended portion 60 of the shaft 84. The lower central portion of
- the bracket 102 is provided with a bearing 108 for the vertical shaft 89. At the upper end of the vertical shaft 89 is the horizontal bevel gear 103, which meshes with both the bevel gears 104 and 105 on diametrically opposite sides, the latter being mounted loosely on the shaft 84. The clutch 109 is splined to the shaft 84 and may be operated by means of the lever 110, which is pivoted at 111 to the auxiliary bracket arm 112. It 70 will now be seen that when the clutch 109 is moved to throw in the gear 104, the rope drum 92 will be operated in one direction, and when the clutch 109 is thrown in to operate the gear 105, the rope drum 92 will 80 be operated in the opposite direction. This reversal of the rope drum 92 is thus effected without changing the direction of rotation of the electric motor.
- The frame 113 for the chain cutter 114 85 comprises a longitudinal central bar 115, which is affixed at its ends to the vertical portions of the said frame, as shown in Fig. 2. The bar 115 is provided with a slot or opening 116 at its inner end into which extends a bracket arm 117 from the lateral face of the motor frame 47, to which it is secured, as shown in Fig. 5. Extending loosely through an opening in the outer end of the bracket arm 117 is a screw-threaded 90 rod or bolt 118, which is rigidly secured at its inner end to the block 119, as shown in Figs. 2 and 5. The block 119 is firmly fastened to the vertical bar 120 of the chain cutter frame. On one side of the bracket 100 117 is located the nut 121, and on the other side of the bracket is the nut 122. By means of this construction, when the nut 121 is loosened and turned back, the nut 122 may be tightened up to move the entire chain 105 cutter frame forward, the frame being supported by the longitudinal bar 115 sliding through the guideways 123 at the outer end of the bracket 124, which is secured to the upper end of the head 75 of the main frame 110 of the mining machine. When the nut 122 is loosened and turned back and the nut 121 is tightened up, the cutter chain frame 113 may be moved rearwardly. When both the nuts 121 and 122 are firmly tightened 115 against the faces of the bracket 117, the cutter chain frame is held firmly in adjusted position against movement either forwardly or rearwardly. The guideways 123 may be so constructed as to prevent any lateral 120 movement of the cutter chain frame, and to hold the latter securely in a vertical plane.
- When the electric motor 47 is operated in the proper direction, the sprocket 55 will be turned so as to move the upper portion of 125 the chain cutter forward over the guideways of the frame 113 and around the sprockets 125.
- By this operation, the vertical kerf 21 may be produced while the gear 73 is being 130

slowly turned and moving the cutter frame forward by engaging the rack 74, the forward movement being in the direction of the arrow 23, shown in Fig. 1. When it is desired to retract the chain cutter from the kerf 21 in the direction of the arrow 24, the lever 70 is moved to reverse position, when the pinion 73 will be more quickly rotated to secure a comparatively quick return of 10 the chain cutter.

Referring now to Figs. 7, 8 and 10, which illustrate the long wall machine designated 25 in Fig. 1, it will be seen that the machine is mounted at one end on the U-shaped track 124. On the track 124 is a truck comprising the wheels 127. This truck is pivoted at 15 128 (Fig. 7) to the main frame 126 of the long wall mining machine. The pivotal connection between the frame 126 and the truck 125 may comprise a cylinder 129, which is rigidly secured to the frame 126 and extends downwardly through a circular opening in the lower portion of the truck 125 and is kept in place by means of the 20 cross-pin 130. The forward portion of the frame 126 is provided with a depending cylindrical lug 131, which rests on the platform 31 and is adapted to slide over the same.

30 The U-shaped track 124 is placed in position so as to be substantially perpendicular to the mine wall, as shown in Fig. 1, and as shown in Fig. 10 the rear portion is extended upwardly and pivoted at 132 to a truck which comprises the wheels 133 running on the rails 11 of a track which is laid substantially parallel to the mine wall, but at a distance therefrom about equal to the length of the U-shaped track 124. Another track is 35 laid outside of the one just referred to and comprises the rails 33 on which run the flat cars 32. The platform 31, as indicated by the dotted line 137 in Fig. 10, extends from the face of the mine wall upwardly over the track to which the U-shaped track 124 is pivoted, as shown in Fig. 9. This truck comprises longitudinal beams 138, 138', which extend beyond the axles 139, 139' at both ends of the truck. The rear end of the 40 beam 138' is cut away at 140, so as to permit the track 124 to extend in an inclined direction, as shown in Fig. 10, and to give the track 124 an additional support. The forward ends of the beams 138 and 138' may 45 be similarly constructed, so as to afford suitable supports for the inclined platform 31. This platform may be pivoted to the beam 138, if desired, in the manner indicated for the pivotal connection between the track 124 and the rear end of the beam 138.

50 The specific construction of the long wall mining machine diagrammatically illustrated in Fig. 1, is illustrated in Figs. 7, 8 and 10. An electric motor 141 rests in suitable bedways 142 on the main frame 126 of

the mining machine. A pinion 143 on the motor shaft meshes with the large gear 144. A sprocket wheel 145 is mounted at the outer end of the shaft 146. A cutter chain 147 extends over the cutter frame 148, which is 55 supported from the motor frame by means of a bracket 149. Extending longitudinally of the cutter frame 148 along the center of the same is a bar 150, the forward portion of which slides over the bracket 151 on the 60 main frame (see Figs. 7 and 8). Extending laterally from the longitudinal bar 150 is a bracket 152 provided with an opening through which freely passes the screw-threaded rod 153, on which are located nuts 80 154 and 155 on opposite sides of the bracket 152. The screw-threaded rod 153 is secured to the bracket 149 at 156 so that it cannot rotate or move longitudinally with respect to the said bracket. By loosening the nut 154, 85 and tightening up the nut 155, the cutter frame 148 may be moved forwardly to take the slack out of the cutter chain 147. The nut 155 may then be moved against the bracket 152 to secure the frame 148 in adjusted position. By loosening the nut 155 and tightening the nut 154, the frame 148 may be moved backwardly to produce slack 90 in the chain 147, if it is to be repaired by substituting a new link for a worn out or 95 injured one.

It will be observed that the shaft 146 shown in Figs. 7 and 8 is supported by brackets 157 and 158, which form fixed bearings for the said shaft. At the outer end of 100 the shaft 146 is a gear 159, which meshes with an idler 160 and this in turn meshes with the gear 161. The latter is connected to a sleeve 162, which is mounted in the lower portion of the bracket 158 and surrounds the shaft 163. The latter extends entirely across the rear portion of the motor to a small pinion 164, which meshes with the 105 rack 165 on the bar 166 which extends longitudinally along one side of the main frame 110 of the machine, as shown in Fig. 7.

Also mounted on the shaft 146 is the intermediate gear 167, which meshes with the gear 168 on the sleeve 169 which turns loosely on the shaft 163. By operating the clutch 170, by means of the lever 171, in one direction or the other, the pinion 164 may be rotated in a corresponding direction. The clutch 170, therefore, is a reversing device for changing the direction of feed of the 120 cutter frame toward or away from the mine wall. If desired, the gear 144 may be directly connected to the sprocket 145, so that when the electric motor is operated by any suitable controlling device the cutter chain 125 will immediately begin to move about the frame 148. When the current of the motor is turned on, and the cutter chain is actuated, the clutch 170 may be thrown in the proper direction to cause the cutter chain 130

frame to be gradually fed forward. Preferably, the forward movement is comparatively slow and the rearward or reverse movement comparatively fast.

5 At an intermediate point on the shaft 146 is keyed a worm 172, which meshes with the worm wheel 173 between the bearings 174 and 175 which are firmly secured to the electric motor frame. The bearing 174 is directly secured to the motor frame, and the bearing 175 is secured to the bearing 174 by the cross piece 176, as shown in Figs. 7 and 8. Extending through bearings 174 and 175 and the worm wheel 173 is a longitudinal shaft 177, which is provided with a longitudinal slot 178, into which extends a spline or feather from the worm wheel 173, so that the latter may slide along the shaft 177. The rotation of the worm wheel 173 will therefore be transmitted to the shaft 177.

The end portions of the shaft 177 are mounted in additional bearings 179, 180 and 181, 182. The bearings 179 and 180 are supported by the brackets 183 and 184, respectively, which are secured to one end of the main frame of the mining machine. The bearings 181 and 182 are supported at the upper ends of the brackets 185 and 186, respectively, which are secured to the other end of the main frame. Between the brackets 183 and 184 is a vertical bearing 187, and between the brackets 185 and 186 is a vertical bearing 188. Between the bearings 181 and 182 is a sleeve 189, which is splined to the shaft 177 by means of the slot 190 and a feather fitting therein. At the ends of the sleeve 189 are the bevel gears 191 and 192, each of which may mesh with the horizontal bevel gear 193. Connected to the bevel gear 192 is a grooved collar 194, in which extends the yoke 195, which is fulcrumed at 196 and provided with a lever arm 197. The fulcrum 196 is supported by the supplemental bracket 198 extending from the bearing 182. By means of the rod 199, which is pivoted at 200 to the lever arm 197, and the lever 201, which is pivoted to the main frame and connected at 202 to the rod 199, the sleeve 189 may be shifted along the shaft 177, so as to bring the bevel gear 191 or the bevel gear 192 into mesh with the bevel gear 193. This will provide a means of reversing the rotation of the shaft 203 which is keyed to the bevel gear 193 and extends downwardly through the vertical bearing 188, the lower end of this shaft being keyed to the rope drum 204 on the inner side of the main frame of the machine and to the rope drum 205 on the under side of the said main frame, as shown in Fig. 7. It will therefore be understood that when the lever 201 is actuated in one direction the bevel gear 191 will mesh with the bevel gear 193 to produce a certain rotation of the rope drums 204 and 205, and that when the lever 201 is reversed

the bevel gear 192 will mesh with the bevel gear 193 and effect a reversal of rotation of the rope drums 204 and 205.

Similar mechanism for effecting reversal of rope drums is shown at the other end of the mining machine. A lever 206 is provided with a yoke, the lower ends of which are pivoted at 207 to the bracket 184, as shown in Figs. 7 and 10. The yoke 208 is provided with inwardly extending lugs 210, which fit into a circular groove in the collar 211 which is fixed to the bevel gear 212. Between the latter and the bevel gear 213 is a sleeve 214, which is splined to the slot 215', and it is therefore free to slide longitudinally but must rotate with the shaft 177. The sleeve 214, by means of the lever 206, may be thrust in one direction or the other to cause the bevel gear 213 or the bevel gear 212 to mesh with the horizontal bevel gear 215, which is keyed to the upper end of the shaft 216. This shaft extends through the vertical bearing 187 and is keyed at its lower end to the rope drums 217 and 218, as shown in Fig. 7.

If desired, a brake may be provided for the drums 217 and 218. In this instance, I have shown a lever 219, fulcrumed at 220 to a bracket 221 extending from the bearing 187, as shown in Fig. 8. A brake shoe 222 is pivoted at 223 to the lever 219, and, by downward pressure on the latter, this brake shoe may be brought into contact with the upper surface of the drum 217.

The rope gearing for the long wall mining machine to effect movement of the block of coal indicated at 28 in Fig. 1, onto the platform 32 of the mine car, as indicated by the dotted lines in Fig. 1, will now be described. A rope 224 is secured at one end to the drum 217, and the other end is anchored at 225 to the outer upper end of the U-shaped track 124. Another rope 226 is secured at one end to the drum 218, and at its other end is anchored at 227 to the standard 228, which is located at the rear end of the track 124. The ropes 224 and 226 are wound on the drums 217 and 218 in opposite directions, as shown in Fig. 10, so that when the drum 217 winds up the rope 224 the drum 218 will pay out the rope 226; and when the rope 226 is wound up, the rope 224 will be paid out. By means of these ropes and drums, the truck 125, together with the mining machine thereon, may be positively moved forwardly or rearwardly on the track 124. By means of the brake 222, shown in Figs. 7 and 8, the mining machine may be held stationary in any position to which it is moved, particularly when the rear end of the machine is to be held stationary while the forward end swings around and when the mining machine is to be moved up the inclined portion of the track 124 and loaded onto the truck comprising the beams 138,

138'. The brake 222 may also be applied during the operation of the mining machine to cut the vertical kerf 26 although usually this will not be necessary since the wheels 127 shown in Fig. 7 engage the rails of the track 124 in such a manner as to resist any tendency of the feeding action of the cutter to move the main frame 126 from its adjusted position on the guiding mechanism comprising the track 124 and the plate 31.

At the forward portion of the mining machine, a rope 229 is wrapped around the drum 205 and its other end anchored at the rear end of the platform 31, at a point indicated by the dot 230 in Fig. 1. Another rope 229' is wrapped around the drum 204 and its end anchored at 231 to the forward edge of the inclined platform 31, as shown in Fig. 9. The anchoring of the end of the rope 229' may be done by means of hooks fitting over the edges of the platform. It will be seen that whenever the drums 204 and 205 are rotated, the forward portion of the mining machine will be shifted about its pivot 128.

The operation is such that after the block of coal 28 has been entirely severed from the mine wall and shifted entirely over onto the platform 31, the rope gearing may be operated to cause the long wall mining machine to move the block of coal onto the mine car platform 32. The chain cutter, during lateral movement of the mining machine, may be kept entirely clear from the platform 31 by means of the depending cylindrical lug 131, which is connected to the bottom of the main frame at its forward end, as shown in Fig. 7. When the operator shifts the lever 206 in the proper direction, and substantially at the same time operates the lever 201, the drums 217, 218 and the drums 204 and 205 will be rotated, so as to move the entire mining machine laterally, which will cause the block of coal 28 to be moved along the platform 31 toward the track 11. When the truck 125 reaches the position indicated by the dotted lines 125' in Fig. 1, the lever 206 may be brought to central position, so as to stop the continued forward motion of the truck 125 on the track 124, and the brake 222 applied to hold it there. The lever 201 may be held in operating position, however, which will cause continued operation of the drums 204 and 205, and the outer end of the frame of the mining machine will move through the arc 232, shown in Fig. 1, and the outer end of the cutter and the block of coal will describe the arc 233. When the block of coal is fully on the platform 31, as indicated in Fig. 1, the lever 201 may be brought to central position to stop the rotation of the drums 204 and 205. The lever 201 should then be reversed so as to cause reverse rotation of the drums 204 and 205, which will swing the mining machine about its pivot, through the arcs 232 and 233, and back to its longitudinal position parallel to the mine wall, when the lever 206 can be thrown in to reverse the rotation of the drums 217, 218 and cause the truck 125 to be moved back toward the mine wall. When the machine is back to its initial position, the mechanism may again be fed forward to produce another cut and sever another block of coal. Whenever desired, the truck 124 and the platform 31, together with the mining machine, may be moved forward to a new location by moving the truck on the rails 11, 11, forward. This may be done while the mining machine is in the dotted line position indicated in Fig. 1, or by moving the rear end of the mining machine up the inclined portion of the track 124 after the block of coal 28 has been moved onto the car platform 32. In such case, the lever 201 could be moved to reversing position, so that when the rear portion of the mining machine is being moved up onto the track the forward portion would be moved backwardly and kept from moving off the outer edge of the platform 31.

The outer end of the track 124 can be lifted when the mining machine is at the upper end of the incline of the track 124 and then blocks at 140 relied upon to hold the inclined portion horizontal temporarily. Furthermore, if the electric motor 141 is stopped when the mining machine reaches the desired position on the truck, and the bevel gear 215 is kept in mesh with one of the bevel gears 212 or 213, the worm 172 and the worm gear 173 may be relied upon to lock the drum 217 against reverse rotation. The mining machine would then be held on the truck at the upper inclined portion of the track 124 by the rope 224. In a similar manner, by keeping the lever 201 in a position where the bevel gear 193 is in mesh with the bevel gear 191 or 192, the drum 205 will also be locked against reverse rotation by the worm gearing associated with the longitudinal shaft 177. The rope 229 will then keep the forward portion of the mining machine from moving down the inclined portion of the platform 31.

It should be understood that in the same manner that the inclined portion of the track 124 may be propped up at 140 so as to be supported in a horizontal position, the plate 31 may be propped up on the forward extension of the beam 138' so that the inclined portion of the plate 31 will be supported in a substantially horizontal position during the transportation of the truck with the mining machine supported on the track 124 and the plate 31, immediately above the truck. As soon as the truck reaches the de-

sired position, the blocks or props at 140 at both ends of the beam 138' may be removed after jacking up the ends of the track 124 and plate 31 adjacent the mine wall and 5 then letting these ends down to the floor adjacent the base of the upright mine wall. Since the track 124 and the plate 31 are pivoted at 132, to the beam 138 of the truck which travels on the mine track 134, the 10 track 124 and plate 31 will adapt themselves to slight irregularities of the floor. That is to say, since the track 124 and the plate 31 are independently pivoted to the truck, they may have some relative flexibility 15 to their downward movement limited by the ends of the beam 138', as shown in Fig. 10. After the guiding mechanism comprising the track 124 and the plate 31 has been let down to the floor to the desired position, the levers 20 201 and 206, shown in Figs. 7 and 8, may be so operated as to move the gear 191 or 192 and the gear 212 or 213, respectively, out of mesh with the horizontal bevel gear 193 and the horizontal gear 215. The mining machine including the frame 126 will then be 25 free to slide down the guiding mechanism by gravity since the worm gear 173 can no longer effect a locking of the rope drums at the end portions of the frame 126, assuming that the ends of the ropes still 30 remain anchored to the ends of the track 124 and the plate 31 at the points indicated in Figs. 7 to 10, inclusive. If desired, the motor 141 may be started and the rope drums 35 operated in the proper direction to positively move the mining machine off the truck down the inclined portions of the track 124 and the plate 31 to the horizontal portions thereof so that the mining machine will be 40 in operating position, as shown in Figs. 1 and 10. When in operating position the 45 brake 222 may be applied manually, but it is preferred to rely on the wheels 127 resting on the track 124, to resist any tendency of the mining machine to move backward during operation to cut the vertical kerf 26, as shown in Fig. 1. It will thus be seen that the rope gearing is useful to move the mining machine laterally from the truck to operating position as well as in the opposite direction to move a block of coal onto the mine car 32. It should also be noted that while the truck carrying the guiding mechanism is being moved to a new position under the 55 next block of coal to be removed, the kerf-cutter may be retracted to initial position relative to the frame 126 and the rope drums operated to move the mining machine back toward the face of the mine wall into position for making the next cut.

It will be understood that those skilled in the art may make various changes in the details and arrangement of parts without departing from the spirit and scope of my in-

vention as defined by the claims and I desire, 65 therefore, not to be restricted to the precise construction herein disclosed.

Having thus described an embodiment of my invention, what I claim and wish to secure by Letters Patent of the United States 70 is:—

1. The combination with a main frame of a mining machine, of kerf-cutting mechanism mounted on said main frame in position to cut a kerf in an upright plane, said kerf-cutting mechanism being movable longitudinally along said main frame, a supporting frame, a pivotal connection between said main frame and said supporting frame, rope gearing for shifting the position of said 75 main frame to locate said kerf-cutting mechanism in various radial positions, said rope gearing comprising a rope winding drum carried by said main frame and a rope extending from said drum with its free end adapted to be anchored during the operation of said winding drum, and a shaft mounted on said main frame and associated with said kerf-cutting mechanism for operation therefrom for the various positions thereof relative to said main frame and said shaft. 80

2. The combination with a main frame of a mining machine, of cutting apparatus mounted on said main frame and movable longitudinally relatively thereto, a shaft 95 mounted on said main frame and associated with said cutting apparatus for operation therefrom for the various positions thereof relative to said main frame and said shaft, a support for the mining machine to which the latter is pivotally connected, and means associated with said shaft and connected to said support to change the radial position of the mining machine with respect to said support. 100

3. The combination with a main frame of a mining machine, of a slotted shaft mounted thereon, a rope drum carried by said main frame, a truck, a pivotal connection between said truck and said main frame, ropes connected between said truck and said rope drum, gearing between said rope drum and said slotted shaft, cutting apparatus mounted on said main frame, and gearing connected to be operated by the source of 115 power of said cutting apparatus and associated with said slotted shaft to secure the operation of said rope drum and the movement of the mining machine to various radial positions. 120

4. The combination with a main frame, of kerf-cutting mechanism mounted on said frame for longitudinal movement thereof in position to cut an upright kerf spaced laterally from one side of said main frame, 125 means for operating said kerf-cutting mechanism including rectilinear feed thereof longitudinally of said main frame and along

the same, a pivotal support for said main frame, and means for swinging said main frame together with said kerf-cutting mechanism on said pivotal support to initially 5 adjust the position of said kerf-cutting mechanism prior to the cutting of a kerf thereby and to subsequently cause the kerf-cutting mechanism to engage the cut block of material and move the same away from 10 the unmined mass.

5. The combination with a platform adapted to be placed in position adjacent a mine wall over which to move mined material toward loading position, of a mining 15 machine comprising a cutter-head, and means for moving said mining machine to cause said cutter-head to engage a severed block of mined material and slide it intact onto said platform.

20 6. The combination with a main frame, of kerf-cutting mechanism mounted on said main frame for movement longitudinally thereof and in position to cut an upright kerf spaced laterally from one side of said 25 main frame, said kerf-cutting mechanism comprising an endless cutter-chain, a motor connected to said kerf-cutting mechanism to move bodily therewith along said main frame, power transmission mechanism 30 between said motor and said chain to drive the latter, feed gearing between said motor and said main frame for moving said kerf-cutting mechanism longitudinally of said main frame while said chain is being driven 35 to effect the cutting of an upright kerf along a mine wall to complete the dislodgment of a large block of solid material from the mine wall, and means for moving the main frame and said kerf-cutting mechanism laterally to cause the kerf-cutting mechanism to engage the block of material and move it intact away from the unmined 40 mass.

7. In a system of mining, the combination 45 with a plate adapted to extend from a position adjacent a mine wall to a mine car, of a mining machine, a track for said mining machine, and means for moving said mining machine along said track to cause the same to engage severed material and move the same over said plate into said mine car.

50 8. The combination with a main frame, of a supplemental frame movable longitudinally of said main frame, kerf-cutting mechanism connected to said supplemental frame to move bodily therewith and mounted in position to cut an upright kerf, a motor mounted on said supplemental frame to move bodily therewith along said main 55 frame, power transmission gearing between said motor and said kerf-cutting mechanism, feed gearing between said motor and said main frame to effect rectilinear feed of said kerf-cutting mechanism to cut a kerf 60 in an upright plane while said main frame 65

remains stationary, and means operated by said motor in any of its positions along said main frame for moving the kerf-cutting mechanism laterally against the dislodged block of material to cause the latter to be 70 moved away from the unmined mass.

9. The combination with a main frame, of a supplemental frame mounted on said main frame for movement longitudinally thereof, a flat frame connected to said supplemental frame to move bodily therewith and mounted in position to enter an upright kerf in a mine wall, a motor mounted on said supplemental frame to move bodily therewith, gearing between said motor and said main frame to effect movement of said upright flat frame into said kerf while said main frame remains stationary, and means operated by said motor in any of its positions on said main frame for moving said 80 flat frame against a block of material to transfer such block of material away from an unmined mass.

75 10. The combination with an elongated main frame, of a supplemental frame slid- 90 able along said main frame, means connected to said supplemental frame to move bodily therewith and mounted in position to be adapted to be inserted into a kerf in a mine wall back of a large block of severed 95 material, means for sliding said supplemental frame longitudinally along said elongated frame, means for moving the elongated frame and supplemental frame laterally to effect shifting of the block of severed material away from the unmined mass, and a single motor for operating both the shifting means and the mechanism for sliding the supplemental frame along said elongated frame.

100 11. The combination with a main frame, of a supplemental frame movable longitudinally of said main frame, an upright flat frame connected to said supplemental frame to move bodily therewith and mounted in 110 position for insertion into an upright kerf in a mine wall, a pivotal support for said main frame, self-acting power-operated mechanism comprising a motor, for moving said main and supplemental frames laterally 115 to cause said upright flat frame to engage the mined material to move the same from its native position toward a mine car for loading, and means operated by the same motor for moving the supplemental frame 120 together with said upright flat frame longitudinally of said main frame in either direction to adjusted positions.

12. The combination with a main frame, of a wheel mounted support adapted to run 125 on a track, a pivotal connection between said wheel mounted support and said main frame, a supplemental frame movable longitudinally of said main frame, an upright flat frame connected to said supplemental frame 130

to move bodily therewith, means for moving said supplemental frame along said main frame to insert said flat frame into a kerf in a mine wall, means for swinging said main frame and said supplemental frame on said pivotal connection as an axis, and means for moving the wheel mounted support along the track to co-act with said swinging means to effect lateral movement 10 of both the main and supplemental frames.

13. The combination with a main frame, of an upright flat frame mounted thereon to move laterally therewith, a wheel mounted support adapted to run on a track, a pivotal connection between said support and said main frame, means for shifting said main frame and said flat frame on said pivotal connection as an axis to move away from its native position a large block of material 20 engaged by said flat frame, and means connected to the rear portion of said main frame for moving said main frame laterally away from the mine wall to shift the position of the pivotal connection between said main frame and said support.

14. The combination with an elongated main frame, of a supplemental frame movable longitudinally of said main frame, a plane kerf-cutter connected to said supplemental frame to move bodily therewith and mounted in position to cut an upright kerf in a mine wall, means comprising a motor for driving said kerf-cutter, mechanism driven by said motor for effecting the feed 35 of said kerf-cutter by movement of said supplemental frame along said main frame, and mechanism operated by the same motor for moving said kerf-cutter laterally against dislodged material to move the latter away 40 from the unmined mass.

15. The combination with a supporting frame, of an upright frame mounted thereon, means for inserting said upright frame in an upright kerf adjacent a large severed 45 block of material at a mine wall, power-operated mechanism for bodily moving said supporting frame and said upright frame to cause the latter to engage said severed block of material and move the same away 50 from the mine wall by translatory lateral movement of said frames, and means for rendering a portion of said power-operated mechanism ineffective to cause further lateral movement of said frames while the 55 other portion of said power-operated mechanism remains effective to cause angular movement of said frames to move the severed block of material onto another position.

16. In a system of mining coal, the combination of a long wall mining machine for severing blocks of material from a mine wall, and means arranged both forwardly and rearwardly of said mining machine for 65 effecting both translatory and rotary move-

ment of the latter to shift the severed block of material to a predetermined position for loading.

17. In a system of mining coal, the combination with a long wall mining machine 70 for severing material in blocks previously cut by intersecting kerfs transversely of a mine wall, of a platform associated with said long wall mining machine and extending upwardly to an elevation approximately equal 75 to that of a platform of a mine car, and mechanism for moving said long wall mining machine bodily to shift the severed block of material over said platform and off the upper end thereof onto the mine car. 80

18. In a system of mining coal, the combination with a long wall mining machine for severing material from a mine wall having intersecting kerfs cut into the same transversely thereof, of a platform associated 85 with said mining machine and extending toward loading position, and means for moving the mining machine to shift the block of material along said platform toward loading position. 90

19. The combination with a stationary inclined plane, of a frame adapted to enter a narrow upright space between a large block of material and the unmined mass adjacent the same, and means for moving said 95 frame to cause the same to push such large block of material away from the unmined mass over such stationary inclined plane toward loading position.

20. The combination with a long wall 100 mining machine, of a support adapted to rest on the mine floor with said mining machine mounted thereon, and means for moving said mining machine laterally and relatively to said support while the latter rests 105 on the mine floor, to shift the severed material from the mine wall over such support toward loading position.

21. The combination with a long wall mining machine, of an inclined plate associated therewith, and means for moving said mining machine to shift severed blocks of material over said inclined plate while the latter remains stationary. 110

22. The combination with an inclined 115 plate extending from the base of a mine wall upwardly to an elevation approximately equal to that of a platform of a mine car, of an upright flat frame adapted to enter an upright narrow space back of the upright face of the unmined mass, and means for effecting bodily rectilinear movement of said frame and swinging thereof to shift the severed block of material over said inclined plate onto said mine car. 120

23. The combination with a long wall mining machine comprising mechanism for cutting a kerf along a mine wall in an upright plane, of a track extending from a position 130

adjacent the mine wall transversely thereof, a wheeled support on said track, a pivoted connection between said wheeled support and said mining machine, and means for 5 swinging said mining machine on said pivotal connection and for moving said support and said mining machine along said track to effect the shifting of a block of material from the mine wall in a transverse direction 10 relatively thereto.

24. The combination with a mining machine comprising mechanism for cutting a kerf along a mine wall in an upright plane, of a track extending transversely of the 15 mine wall from a position adjacent the same, a truck on said track to pivotally support one end of said mining machine, mechanism adapted to rest on the floor of the mine chamber adjacent the mine wall for slidably 20 supporting the other end of said mining machine, and means for moving said mining machine to cause it to shift severed blocks of material away from the unmined mass.

25. The combination with a mining machine, of a track for said mining machine, a pivotal support for said mining machine, a plate associated with said mining machine in position to receive material severed thereby, and means for moving said mining 30 machine on said track and on its pivotal support to shift a severed block of material over said plate and off the same.

26. The combination with a frame adapted to extend along a mine wall between the 35 unmined mass and a large block of material adjacent said unmined mass, of a plate extending from the base of the mine wall under such dislodged material toward loading position, a pivotal support for one end of 40 said frame, the other end of said frame being supported by said plate, a track for said pivotal support, and means for moving said frame along said track and along said plate and also swinging said frame on said pivotal support to shift the block of dislodged material away from the mine wall and over 45 said plate and off the same.

27. The combination with a frame adapted to extend along a mine wall in an upright 50 plane in a narrow space between a large block of material and the unmined mass adjacent thereto, of a track for the rear portion of said frame, said track being perpendicular to the mine wall and extending to 55 a position adjacent the same, a pivotal support for said frame and adapted to run on said track, and means for moving said frame rectilinearly along said track and for moving said frame on said pivotal support to 60 effect the shifting of such block of severed material transversely of the mine wall and away from the same.

28. The combination with a frame adapted 65 to occupy the space between a block of material and the unmined mass, such space

being in an upright plane, rope gearing connected to the end portions of said frame, and means for operating said rope gearing and controlling the same to effect movement of the said frame bodily or rotation of the 70 same at will on an upright axis to shift the severed block of material from its native position.

29. The combination with a mining machine having an upright kerf cutter frame 75 adapted to be extended into an upright space between a block of material and the unmined mass adjacent the same, rope gearing connected to the end portions of said mining machine, and means for operating said rope 80 gearing to effect both translatory and rotary movement of the mining machine to cause the kerf cutter frame to engage the block of severed material and move the same from its native position toward loading position 85 spaced from the mine wall.

30. The combination with a long wall mining machine, of a track substantially at right angles to the mine wall, a pivotal support for the rear portion of the mining 90 machine on said track, an inclined plate associated with said mining machine and extending to an elevation approximately equal to that of a platform of a mine car, and rope gearing connected to the end portions 95 of the mining machine to move the latter on the said track or swing the same about the said pivotal support to effect the shifting of a block of severed material from a mine wall over said inclined plate and off the same 100 onto a mine car.

31. The combination with a mining machine comprising kerf cutting mechanism having a flat upright cutter frame, and comprising also means for feeding the kerf cutting mechanism along an upright plane, of a wheeled support for one end of said mining machine, a pivotal connection between said wheeled support and said mining machine, rope gearing connected to the rear portion of said mining machine, additional rope gearing connected to the forward portion of said mining machine, and means for operating said rope gearing for shifting said mining machine to various radial positions 115 and for shifting said mining machine laterally to various distances from the mine wall to effect movement of a dislodged block of material from the mine wall.

32. The combination with a main frame, 120 of a supplemental frame movable relatively to said main frame, an upright kerf-cutter connected to said supplemental frame, means comprising a motor for operating said kerf-cutter including feed thereof by movement 125 of said supplemental frame along said main frame, a pivotal support for said main frame, rope gearing connected directly to said main frame for swinging the same together with said supplemental frame and 130

said upright kerf-cutter on said pivotal support as an axis and thereby move such kerf-cutter laterally to cause the same to engage a severed block of material and move 5 the same away from the mine wall, and means between said motor and said rope gearing for operating the latter at the will of the operator irrespective of the position of said supplemental frame relative to said 10 main frame.

33. In a mining machine, the combination with a supporting frame, of a kerf-cutter mounted on said supporting frame in position to cut a kerf in a substantially vertical 15 plane, means for operating said kerf-cutter including feed thereof longitudinally along said frame, a support to which said frame is pivoted, rope-gearing to effect movement 20 of said support along a path extending transversely of said supporting frame, additional rope gearing connected to the supporting frame at a position remote from its 25 pivotal connection to said support, and means for operating and controlling both of said rope gearings to effect lateral translatory movement of said supporting frame and said kerf-cutter or angular movement thereof relatively to said support.

34. In a mining machine, the combination 30 with cutting apparatus, of means for actuating the same, a supporting frame for said cutting apparatus and said actuating means, means for feeding said cutting apparatus and said actuating means longitudinally 35 along said frame, rope gearing for shifting the position of said frame radially, additional rope gearing coöperating with said first named rope gearing for shifting the position of said frame laterally, and means 40 for transmitting power from said actuating mechanism to both of said rope gearings irrespective of the position of said actuating means along said frame.

35. In a mining machine, the combination 45 with mechanism for cutting an upright kerf in a mine wall, of an elongated supporting frame, means for actuating said kerf cutting mechanism, said means comprising a motor mounted on said frame and guided along 50 the same, means for feeding said kerf cutting mechanism by moving said motor and said actuating mechanism and said kerf cutting mechanism along said frame, rope gearing comprising a rope winding drum mounted 55 on said frame for shifting the position of the latter to adjust the position of said kerf cutting mechanism, and means comprising relatively sliding elements for transmitting power from said motor to said rope winding drum irrespective of the position of 60 said actuating mechanism and said motor along said frame.

36. In a mining machine, the combination 65 with mechanism for cutting an upright kerf in a mine wall, of means for actuating said

kerf cutting mechanism, a relatively stationary frame for supporting and guiding said kerf cutting mechanism and said actuating means, means for feeding said kerf cutting mechanism and said actuating means 70 along said frame, rope gearing connected to one end portion of said frame for swinging the latter on the other end portion thereof as a pivot, said rope gearing comprising a rope drum carried by said frame, a longitudinal shaft mounted on said frame and connected to said rope drum, and mechanism associated with said actuating means and comprising a gear sliding on said longitudinal shaft for transmitting power to said 80 rope gearing irrespective of the position of said actuating means and said kerf cutting mechanism along said frame.

37. In a system of mining, the combination with mechanism having a supporting 85 surface extending from the floor of a mine chamber adjacent an upright mine wall backwardly therefrom to an elevation approximately equal to that of the platform of a mine car, and self-acting power-operated mechanical means adapted to extend along a mine wall back of a severed block of material and move the same away from the mine wall over said surface and off the upper end thereof onto said mine flat car. 90

38. In a system of mining, the combination with an inclined plate adapted to extend from the floor of a mine chamber to an elevation approximately equal to that of a platform of a mine car, of a mining machine, a track for said mining machine, and means for moving said mining machine along said track to cause the same to engage severed material and move the same 100 over said plate into a mine car. 105

39. In a system of mining, the combination with an inclined plate, of a track, a truck for supporting said plate at one end thereof and said track at the other end thereof, a frame supported by said track 110 and said plate, means extending from said frame for engaging severed material, and means for moving said frame over said track and plate to cause said engaging means to move such severed material upwardly over the said plate into a mine car adjacent to the upper end of said plate. 115

40. In a system of mining, a combination with a truck, of a track pivotally connected to said truck and extending laterally 120 therefrom toward a mine wall, a plate pivotally connected to the other end of said truck and also extending toward the mine wall, said track and said plate being inclined and curved correspondingly to a substantial 125 horizontal plane at the mine wall, a frame partly supported by said track and partly by said plate, an extension from said frame for engaging a block of material severed from the mine wall, and means connected to 130

the forward and rearward portions of said frame for moving the same to cause said extension to transfer said block of material upwardly over said plate into a mine car adjacent to the upper end of said plate.

41. In a system of mining, a combination with a truck, of a track pivoted to one end thereof and extending laterally therefrom toward the mine wall, a plate pivoted to the other end of said truck and extending toward the mine wall, a mining machine comprising an upright kerf cutter having a frame adapted to engage a severed block of material at the mine wall, a pivotal connection between the rear end of said mining machine and of said track, and rope-gearing mechanism connected to the forward and rear portions of said mining machine to secure movement of said kerf cutter frame laterally over said plate to effect the transfer of said severed block of material upwardly over said plate to a mine car adjacent to the upper end of said plate.

42. In a system of mining, the combination with a truck adapted to run on a track substantially parallel with the face of an upright mine wall, of a plate pivoted to that side of said truck remote from the mine wall, said plate having a horizontal portion adapted to rest on the floor of the mine chamber adjacent said mine wall and an inclined portion extending from said horizontal portion upwardly over its pivotal connection to said truck to the upper surface of a mine car adapted to run on a track parallel to the first named track, an upright frame adapted to extend into a narrow upright space between a block of material and the upright face of the mine wall, and means for moving said frame to cause the same to engage said block of material and move the latter over said plate onto said mine car.

43. In a system of mining, the combination with a truck, of a plate pivoted to said truck on that side thereof remote from the face of the mine wall and extending from the truck to a receiving position adjacent the mine wall, a mining machine comprising an upright kerf cutter adapted to extend along the face of the mine wall back of a block of material, means for moving said mining machine laterally to engage the block of material and move the same along said plate and off the same to loading position, and mechanism pivotally connected to said truck for guiding said mining machine during its lateral path of travel.

44. In a system of mining, the combination with a truck, of a track pivotally connected to one end of said truck on that side thereof remote from a mine wall extending parallel to the track on which the truck runs, a plate pivotally connected to the other end of said truck, said pivoted plate and said pivoted track being inclined down-

wardly from the truck and curved correspondingly to a substantially horizontal plane at the mine wall, a long wall mining machine comprising a kerf cutter in a substantially vertical plane, said mining machine being supported partly by said track and partly by said plate, rope gearing connected to the rear portion of said mining machine and anchored to the ends of said pivoted track, additional rope gearing connected to the forward portion of said mining machine and anchored to the ends of said plate, and means for independently controlling the operation of each of said rope gearings to effect lateral rectilinear movements of said mining machine and swinging movements thereof to cause said kerf cutting mechanism to engage the dislodged block of material and move the same over said plate to loading position on a mine car adapted to run on a track substantially parallel to the face of the mine wall.

45. In a system of mining, the combination of a truck, a plate connected to said truck and inclined downwardly therefrom to a substantially horizontal portion adapted to occupy a receiving position adjacent the face of an upright mine wall, said plate having its inclined portion and its horizontal portion connected to move rectilinearly and parallel to the path of travel of said truck, and means in position to move material from the mine wall over said plate.

46. In a system of mining, the combination with a truck, of a plate having a horizontal portion adapted to occupy a receiving position adjacent an upright mine wall, said plate having also an inclined portion extending upwardly from said horizontal portion over the path of travel of said truck, means on said truck for supporting said inclined portion of said plate, and means adapted to be located at the receiving portion of said plate to move material over said plate.

47. In a system of mining, the combination with a truck, of a plate having a horizontal portion adapted to rest on the floor of the mine chamber adjacent the face of an upright mine wall, said plate having an inclined portion extending upwardly from said horizontal portion over the path of travel of said truck, a pivotal connection between the inclined portion of said plate and said truck, and means for severing material from the mine wall and moving it along said plate.

48. In a system of mining, the combination with a truck, of a plate pivoted to said truck and adapted to extend across the path of travel of said truck to a receiving position adjacent a mine wall, a seat on said truck for limiting the downward movement of said plate relatively to said truck, and means adapted to ride over said plate in

position to move material from the mine wall over said plate.

49. In a system of mining, the combination with a truck, of a plate pivoted to that side of said truck remote from the face of a mine wall extending substantially parallel to the path of travel of said truck, said plate having a substantial horizontal portion adapted to occupy a receiving position at the face of the mine wall, and said plate having an inclined portion rigidly connected to said horizontal portion and extending upwardly therefrom across the path of travel of said truck to a mine car having a path of travel parallel to the path of travel of said truck, means on that side of said truck nearer the mine wall for assisting said pivotal connection in supporting said plate, and means for moving material from the mine wall over said plate toward loading position.

50. In a system of mining, the combination with a truck, of a plate pivoted to one side of said truck and extending across the path of travel thereof to a receiving position at a mine wall extending substantially parallel to the path of travel of said truck, means on the other side of said truck for rendering partial support to said plate, and means for moving material over said plate from its receiving edge to the opposite edge thereof.

51. In a system of mining, the combination with a truck, of a plate pivotally connected to one side of said truck, said plate having a horizontal portion adapted to rest on the floor of a mine chamber adjacent an upright mine wall, and said plate having an inclined portion rigidly connected to said horizontal portion and extending upwardly therefrom across the path of travel of said truck to loading position on a mine car having a path of travel substantially parallel to the path of travel of said truck, a seat on the other side of said truck for an intermediate portion of said plate, and means for engaging a large block of material at the mine wall and moving said block over the horizontal and inclined portions of said plate.

52. In a system of mining, the combination with a truck, of a track pivotally connected to one side of said truck and extending across the path of travel of said truck downwardly on an incline to a horizontal portion of said track, a seat on the other side of said truck for the intermediate portion of said track, a mining machine mounted on said track, and means for moving said mining machine from the horizontal portion of said track onto the upper inclined portion thereof.

53. In a system of mining, the combination with a mining machine, of a truck adapted to support said mining machine,

guiding mechanism pivotally connected to said truck and having a downwardly inclined portion for directing the mining machine from said truck onto a horizontal portion of said guiding mechanism, and a seat for engaging an intermediate portion of said guiding mechanism for supporting the latter and the mining machine for transportation.

54. In a system of mining, the combination with a truck, of a track pivotally connected to one side of said truck on an axis extending parallel to the path of travel of said truck, said track extending transversely of the truck on a downward incline to a horizontal portion thereof, means on the other side of said truck in position to engage said track to support the intermediate portion thereof, a mining machine, and means for supporting part of said mining machine while the remainder thereof rests on said track.

55. In a system of mining, the combination with a truck, of a track connected thereto and extending transversely therefrom to a horizontal portion spaced from said truck, a plate connected to said truck and extending transversely therefrom on a downward incline to a horizontal portion spaced from said truck, and a mining machine supported by said track and said plate for movement from a position above the truck to the horizontal portions of said track and said plate.

56. In a system of mining, the combination with a truck, of a track connected to said truck and extending laterally and downwardly therefrom to the floor of a mine chamber, a mining machine movable along said track, rope gearing connected between said mining machine and said track, and means for operating said rope gearing to move said mining machine along said track and laterally off the truck to a position spaced laterally from said truck.

57. In a system of mining, the combination with a truck, of a track connected thereto and extending laterally and downwardly therefrom to a horizontal portion adapted to rest on the floor of a mine chamber, a mining machine movable along said track, and means for moving said mining machine laterally off from said truck along said track to a position spaced laterally from said truck and back onto said truck along said track.

58. In a system of mining, the combination with a truck, of a mining machine adapted to occupy a position extending along said truck above the same, guiding mechanism for one end of said mining machine and connected to one end of said truck, said guiding mechanism being inclined downwardly from said truck to a horizontal portion adapted to rest on the floor of

a mine chamber, means connected to the other end of said truck for supporting the other end of said mining machine and directing it on a downward incline toward the floor of the mine chamber, and apparatus for effecting movement of said mining machine along said guiding mechanism and said support off from said truck, and also movement of said mining machine along said guiding mechanism and said support to its position above said truck.

59. In a system of mining, the combination with a truck, of a track connected to said truck and extending on an incline downwardly therefrom to a horizontal portion, a support adapted to travel along said track, a mining machine pivotally connected to said support on an upright axis, and mechanism for moving said support along 15 said track to adjust the position of said pivotal connection.

60. In a system of mining, the combination with a truck, of a track connected to one end of said truck and extending transversely to the path of travel of said truck on a downward incline to a horizontal portion adapted to rest on the floor of a mine chamber, a plate connected to the other end of said truck and extending downwardly to 25 a horizontal portion adapted to rest on the floor of the mine chamber, a support on said track, a mining machine pivotally connected to said support, rope gearing at one end of said mining machine and anchored to the 30 ends of said track, additional rope gearing at the other end of said mining machine and anchored to the ends of said plate, and means for controlling the operation of each 35 of said rope gearings independently of the other.

61. In a system of mining, the combination with a truck, of guiding mechanism connected to said truck and adapted to extend laterally therefrom toward a position 45 at the mine floor spaced laterally from the mine track on which said truck is mounted, a mining machine on said guiding mechanism adapted to be located in position for support by said truck during transportation along said mine track or in the said 50 position at the mine floor, and mechanism for moving the mining machine laterally over said guiding mechanism to vary the position thereof on or off the said truck.

62. In a system of mining, the combination with a portable supporting frame movable along a path approximately parallel to the face of a mine wall and spaced therefrom, of guiding mechanism connected to 55 said frame for support thereby and movement therewith and adapted to extend from said frame transversely of the path of travel thereof toward the said face, and a mining machine movable laterally over said 60 guiding mechanism from the truck to an

operating position at said face and back laterally onto said truck for transportation to a new position.

63. In a system of mining, the combination with a truck adapted to travel on a mine track, of guiding mechanism thereon adapted to extend laterally from said truck to a position spaced laterally from said mine track, a mining machine movable transversely over said guiding mechanism 75 onto and off said truck, and draft mechanism for positively moving said mining machine transversely of itself from the truck to an operating position and back onto said truck for transportation to a new position. 80

64. In a system of mining, the combination with a truck adapted to travel on a mine track, of tiltable guiding mechanism pivoted to said truck and adapted to extend toward the floor of the mine chamber 85 laterally from said truck to a position spaced laterally from said track, and a mining machine mounted on said guiding mechanism for movement over the latter from a supporting position over said truck, toward the 90 floor of the mine chamber for operation in a position spaced laterally from said mine track.

65. In a system of mining, the combination with a truck, of guiding mechanism 95 connected to said truck and extending laterally therefrom, a mining machine mounted on said guiding mechanism for movement laterally from the truck toward the upright face of a mine wall spaced laterally from said truck, and mechanism for moving the mining machine laterally of itself off the truck over said guiding mechanism into position for mining while still supported by 100 said guiding mechanism.

66. In a system of mining, the combination with a truck, of guiding mechanism connected to said truck and extending laterally therefrom, a mining machine mounted on said guiding mechanism for movement 110 transversely of itself or laterally from supporting position on said truck to an operating position at that end of said guiding mechanism remote from the truck, and rope gearing anchored to the lateral edges of said 115 guiding mechanism and connected to said mining machine to adjust the position of the latter by sidewise movement thereof on said guiding mechanism.

67. In a system of mining, the combination with a truck, of a track extending laterally from the rear end of the truck, a plate extending laterally from the forward end of said truck, a mining machine mounted on said track and said plate and movable along 120 said track and plate laterally from the truck toward a mine wall spaced laterally from the truck, and means for moving the mining machine over said track and plate and for holding the mining machine in adjusted 125 130

operating position at the mine wall while supported on said track and plate.

68. In a system of mining, the combination with a truck, of a track connected to the rear end of said truck and extending laterally therefrom toward the face of a mine wall, a plate connected to the forward end of said truck and extending laterally therefrom toward said face; a mining machine mounted on said track and said plate for movement from the truck to the said face, draft mechanism comprising a rope drum for moving the rear end of the mining machine along said track, means for moving the forward end of the mining machine along said plate, and a brake applicable to said rope drum to cooperate with the connection of said mining machine to said track to hold the mining machine stationary in its adjusted operating position at the face of the mine wall.

69. In a mining machine, the combination with a main frame, of a supplemental frame movable longitudinally relatively thereto, cutting apparatus mounted on said supplemental frame and movable therewith, a motor on said supplemental frame connected to said cutting apparatus, rope gearing connected to said main frame and adapted to adjust the position of the latter together with said cutting apparatus, means comprising worm gearing connected between said motor and said worm gearing for operating the latter, and controlling mechanism for causing said worm gearing to lock said rope gearing in adjusted position to cause said main frame to be held in predetermined position during the operation of said cutting apparatus.

70. In a mining machine, the combination with a main frame, of a supplemental frame movable longitudinally thereof, cutting mechanism mounted on said supplemental frame for movement therewith, means for operating said cutting mechanism, rope gearing connected to said main frame and adapted to adjust the position thereof, and means comprising locking worm gearing connected between said rope gearing and the source of power of said operating means to actuate said rope gearing and hold the same in adjusted position.

71. In a mining machine, the combination with supporting framework, of cutting mechanism mounted thereon for bodily movement relatively thereto, power transmission mechanism for operating said cutting mechanism including bodily movement thereof relatively to said framework to secure feeding of said cutting mechanism, rope gearing connected to said framework and adapted to adjust the position of the latter together with the cutting mechanism mounted thereon, and means comprising locking worm gearing between said rope

gearing and said power transmission mechanism to effect the actuation of said rope gearing and the holding thereof in adjusted position.

72. In a mining machine, the combination with supporting framework, of cutting mechanism mounted thereon for bodily movement relatively thereto, power transmission means for operating said cutting mechanism including feeding movement of the latter by bodily movement thereof relatively to said framework, rope gearing comprising a rope drum mounted on said framework, means comprising worm gearing connecting said rope drum to said power transmission means, and means for connecting said rope drum to said worm gearing to cause the latter to hold said rope drum in adjusted position while said power transmission means is inactive.

73. In a mining machine, the combination with a main frame, of a supplemental frame movable longitudinally of said main frame, kerf-cutting mechanism connected to said supplemental frame to move bodily therewith, a motor mounted on said supplemental frame to move therewith, power transmitting mechanism between said motor and said kerf-cutting mechanism for driving the latter, power transmitting means between said motor and said main frame for moving said supplemental frame along said main frame to secure feeding movement of said kerf-cutting mechanism, a shaft extending longitudinally of said main frame, worm gearing connected between said motor and said shaft to rotate the latter although slideable along the same, rope gearing comprising a rope drum mounted on said main frame, and means for connecting said rope drum to said shaft to cause the rotation of said rope drum when said worm gear is operated and to effect the locking of said rope drum when said worm gear is not being rotated.

74. In a mining machine, the combination with a main frame, of a supplemental frame movable along said main frame, kerf-cutting mechanism carried by said supplemental frame to move bodily therewith, a motor on said supplemental frame, means comprising a transverse shaft between said motor and said kerf-cutting mechanism for driving the latter, mechanism comprising racks and pinions for moving the supplemental frame along said main frame to secure feeding movement of said kerf-cutting mechanism, clutch mechanism for reversing the movement of said supplemental frame along said main frame, a shaft extending longitudinally of said main frame, rope gearing comprising a rope drum mounted on said main frame, worm gearing connected between said transverse shaft and said longitudinal shaft, and means for connecting said longitudinal shaft to said rope

drum to effect the rotation of the latter when said last-named clutch is thrown in and to effect the locking of said drum by said worm gearing when said last-named clutch is thrown out.

75. In a mining machine, the combination with a main frame, of a supplemental frame, cutting apparatus mounted on said supplemental frame and movable bodily therewith, power transmission mechanism for operating said cutting apparatus including feeding movement thereof, rope gearing connected to the end portions of said frame and comprising two pairs of rope drums, one pair at the forward portion of said main frame and the other pair at the other end portion of said main frame, means comprising worm gearing for transmitting power to said rope drums, and means for controlling the operation of the forward pair of rope drums independently of the rear pair of rope drums.

76. In a system of mining, the combination with a truck adapted to travel on a mine track, of guiding mechanism comprising a track and a plate pivoted independently to the end portions of said truck and extending laterally therefrom toward the face of the mine wall, and a mining machine mounted on said guiding mechanism for transportation along said track when above said truck and for movement laterally from said truck to an operating position spaced laterally from said track.

77. In a system of mining, the combination with a portable frame, of guiding mech-

anism connected thereto and extending laterally therefrom, a mining machine adapted to be supported on said guiding mechanism above said frame for transportation and adapted to move over said guiding mechanism laterally from the frame to an operating position at the face of the mine wall extending approximately parallel to the path of said portable frame, and means for confining the rear end portion of said mining machine to such lateral movement and preventing movement of the mining machine relatively to said guiding mechanism and said frame parallel to the path of travel of said frame.

78. In a mining machine, the combination with an elongated main frame, of a motor mounted thereon to slide longitudinally thereof, upright kerf-cutting mechanism connected to said motor to move therewith, power transmission mechanism between said motor and said kerf-cutting mechanism, feeding mechanism between said motor and said main frame, and means comprising rope gearing connected to said motor through worm gearing for adjusting the position of said main frame and said kerf-cutting mechanism.

In testimony whereof I have signed my name to this specification, in the presence of two subscribing witnesses, on this 26th day of April, A. D. 1913.

EDMUND C. MORGAN.
